UNITED STATES PATENT OFFICE.

JAMES W. CRONAN, OF PORTAGEVILLE, MISSOURI.

HARNESS BUCKLE.

Application filed April 22, 1926. Serial No. 103,909.

This invention relates to harness buckles and more particularly to a combined back band and trace chain fastener.

An important object of the invention is to produce a device of this character which will securely clamp the back band without any tendency to cut the same, which may be very readily and rapidly adjusted upon the back band and which may be independently operated to either adjust the trace chain or the back band without disturbing the other of these elements.

A further object of the invention is to produce a device of this character which may be readily and cheaply manufactured, which will be durable and efficient in service and a general improvement in the art.

These and other objects I attain by the construction shown in the accompanying drawings, wherein for the purpose of illustration is shown a preferred embodiment of my invention and wherein:—

Figure 1 is a side elevation of a buckle constructed in accordance with my invention employed to connect the back strap and trace chain of harness;

Figure 2 is a front elevation of the buckle with the locking member in the open position;

Figure 3 is a section on the line 3—3 of Figure 1;

Figure 4 is a section on the line 4—4 of Figure 1.

Referring now more particularly to the drawings, the numeral 10 generally designates a plate having at its side edges adjacent its upper end outstanding flanges 11 which are formed with slots 12, for a purpose presently to appear.

40 In the plate above and below these slots are formed transversely extending slots 13 and 14 through which may be passed the web W of the back band so that a portion thereof overlies the front face of the plate 10 between the openings 13 and 14. The plate adjacent the openings 13 and 14 is forced outwardly, as indicated at 15 and 16 so that the web would normally tend to lie in spaced relation to the front face of the plate. The 45 lower end of the plate has a narrow revert 17 confronting the front face of the plate in spaced relation thereto and having its upper end provided with an offset central arm 18 producing at the sides of the revert 50 arms 19 arranged in the plane thereof. Between these arms a shoulder 20 is produced,

the purpose of which will presently appear.

This plate may be constructed in any suitable manner, but, because of its formation, is particularly adapted to a stamping operation. A lock 21 is provided comprising a channeled element, one flange of which is toothed, as indicated at 22, and is adapted to engage the web W between the openings 13 and 14 and force this web into engagement with the front face of the plate. This flange has extensions 23 pivotally engaging in the openings 12 of the flanges 11 of the plate 10. The second flange of the channel, indicated at 24, is made of such length that when the first mentioned flange is in its web clamping position, this second flange tends also to clamp the web against the upper edge wall of the slot 14 so that the web is firmly held against movement. Movement of the locking member 21 to its locking position is limited by the engagement with the front face of the plate 10 below the slot 14 of the angular end portion 25 of a handle 26 with which the locking member is provided as a means for rotating the same.

Slidable upon the handle 26 is a latch including a yoke 27 and bracing the handle and having an end wall 28 confronting the serrated flange at the under side of the handle. Between the serrated flange and the end wall of the yoke a spring 29 is disposed and constantly urges the yoke and latch toward the free end of the handle 26. The lower end of this latch, when the angular end portion of the handle is engaged with the plate 10, is positioned to enter between the arms 18 and 19 and engage against the shoulder 20. The latch may be withdrawn against the action of the spring by engaging with the fingers an angular flange 30 with the upper end of the latch.

The formation of the revert at the lower end of the plate 10 produces a hook 31 which may be engaged in the links L of a trace chain and the trace chain may be adjusted by simply sliding the latch upwardly to open the space 32 between the upper end of the revert and the lower end of the handle. Similarly, when it is desired to adjust the buckle upon the back band, this may be accomplished without shifting the trace chain by simply disengaging the latch and swinging the handle to release the back band and permit movement of the plate 10 thereon.

Attention is directed to the fact that the extensions 23 of the locking member are flat and are so positioned upon the locking member that they extend transversely of the slots when the locking member is in the locking position and longitudinally of the slots when the locking member is open. Thus, when the locking member is in the locking position, it may partake of longitudinal movement upon the plate 10 so that any tendency of the web W to slip will cause the teeth of the locking flange to approach the forwardly pressed portion 15 of the plate 10 and the second flange 24 to approach the upper wall of the slot 14 with the result that the web is more firmly grasped. Thus, it will be noted that the forwardly pressed portions 15 and 16 of the plate while the locking member is in locking position are arranged in confronting relation to the flanges of this locking member. It will, of course, be obvious that the engagement of the flange 22 with the web will firmly hold the web against movement with relation to the plate 10 and any movement of the web which takes place must take place above this flange. In order to prevent sawing of the band against the portion of the plate 10 lying above the upper slot 13 and consequent destruction of the band, a portion of the metal displaced in the formation of the slot 13 is left attached to the plate 10 at the upper edge of the slot, as indicated at 33, the junction of this flange with the rear face of the plate providing a rounded shoulder 34 against which the web may abut so that tendency of the web to wear will be materially decreased. It will, of course, be obvious that the construction hereinbefore set forth is capable of a certain range of change and modification without materially departing from the spirit of the invention and I accordingly do not limit myself to such specific structure except as hereinafter claimed.

I claim:—

1. In a back band buckle, a plate formed with flanges at the side thereof, the plate having slots through which the back band may be threaded to place a portion thereof at the same side of the plate as the flanges, a locking member pivoted between the flanges and including a web engaging flange which, in the locking position of the locking member, is perpendicularly disposed to the plate, the pivotal connection of the locking member with the flanges permitting longitudinal movement of the locking member upon the plate, and a forwardly pressed portion on said plate confronting the flange of the locking member when in the locking position.

2. In a back band buckle, a plate formed with flanges at the side thereof, the plate having slots through which the back band

may be threaded to place a portion thereof at the same side of the plate as the flanges, a locking member pivoted between the flanges and including a web engaging flange which, in the locking position of the locking member, is perpendicularly disposed to the plate, the pivotal connection of the locking member with the flanges permitting longitudinal movement of the locking member upon the plate, a forwardly pressed portion on said plate confronting the flange of the locking member when in the locking position, the lower end of the plate having a revert forming a trace chain receiving hook, a handle for the locking member aligning with the terminal of the revert, and means slidable upon the handle for latching the handle to the revert.

3. In a back band buckle, a plate formed with flanges at the side thereof, the plate having slots through which the back band may be threaded to place a portion thereof at the same side of the plate as the flanges, a locking member pivoted between the flanges and including a web engaging flange which, in the locking position of the locking member, is perpendicularly disposed to the plate, the pivotal connection of the locking member with the flanges permitting longitudinal movement of the locking member upon the plate, a forwardly pressed portion on said plate confronting the flange of the locking member when in the locking position, the lower end of the plate having a revert forming a trace chain receiving hook, a handle for the locking member aligning with the terminal of the revert, means slidable upon the handle for latching the handle to the revert, and a spring between the locking member and the latching means constantly urging the latching means into engagement with the revert.

4. In a back band buckle, a plate formed with flanges at the side thereof, the plate having slots through which the back band may be threaded to place a portion thereof at the same side of the plate as the flanges, a locking member pivoted between the flanges and including a web engaging flange which, in the locking position of the locking member, is perpendicularly disposed to the plate, the pivotal connection of the locking member with the flanges permitting longitudinal movement of the locking member upon the plate, a forwardly projecting portion on said plate confronting the flange of the locking member when in the locking position, the lower end of the plate having a revert forming a trace chain receiving hook, a handle for the locking member aligning with the terminal of the revert, means slidable upon the handle for latching the handle to the revert, and a spring between the locking member and the latching means constantly urging the latching means into

engagement with the revert and locking the flange toward the forwardly projecting portion of the plate.

5. In a back band buckle, a plate having slots through which the back band may be threaded to place a portion thereof at the front of the plate, a locking member pivoted to the plate and engaging said portion of the band to hold the band against movement, the plate having a hook for engagement with a trace link, the locking member having a handle, and a latch shiftable upon

the handle when the locking member is in the locking position and engageable with the bill of the hook to close the opening between the hook and the adjacent end of the handle of the locking member whereby the latch may be withdrawn to permit disengagement of the link from the hook without shifting the locking member from its locking position. ¹⁵

In testimony whereof I hereunto affix my signature.

JAMES W. CRONAN.
